UNITED STATES PATENT OFFICE.

ISAAC N. GASKILL, OF ST. LOUIS, MISSOURI.

AUTOMATIC PRESSURE-REGULATOR AND STOP-VALVE.

SPECIFICATION forming part of Letters Patent No. 530,765, dated December 11, 1894.

Application filed March 29, 1894. Serial No. 505,535. (No model.)

To all whom it may concern:

Be it known that I, ISAAC N. GASKILL, of the city of St. Louis, State of Missouri, have invented certain new and useful Improvements in Automatic Pressure-Regulators and Stop-Valves, of which the following is a full, clear, and exact description, reference being had to the accompanying drawings, forming a part thereof.

10 My invention relates to an improved automatic pressure regulator and stop valve, and consists in the novel construction, combination and arrangement of parts, hereinafter specified and designated in the claims.

15 The object of my invention is to provide an improved device of this class, which shall automatically regulate the passage of steam, or fluid, through the pipe to which it is connected, and which shall automatically act to 20 cut off the flow of steam through said pipe in the event of an accidental destruction, or explosion, of the pipe, or any of the parts to which it is connected.

25 Referring to the drawings: Figure 1 is a side elevation, showing the device as applied for practical use. Fig. 2 is a central longitudinal sectional elevation of the device detached. Fig. 3 is a transverse sectional elevation on the line 3—3 of Fig. 2. Fig. 4 is a 30 transverse sectional elevation on the line 4—4 of Fig. 1. Fig. 5 is a perspective view of the valve-plug.

35 In the construction of the device as shown, the numeral 10 designates a common steam boiler, and 11 an ordinary rendering tank such as is made use of in lard rendering establishments, packing houses, and the like. Extending from the boiler is a steam pipe 12 having a globe, or other common valve, 13 connected 40 thereto for closing said pipe by hand, when necessary. Another steam pipe 14 communicates with the rendering tank 11. Interposed between, and connecting, the steam pipes 12, 14 is a casing 15 having a cylinder 16 integrally formed therewith, and extending vertically therefrom. Transversely mounted in the casing 15 is a valve-plug 17 (Fig. 5) adapted for reciprocatory rotation. Said 45 valve-plug is approximately semi-cylindrical in form, and is provided with two slots 18, 18 arranged parallel but extending longitudinally of said valve-plug one in a plane above

the other. Located at the approximate axis of the valve-plug 17, and extending longitudinally through the same, is a bore 19, which is 55 oval, or elongated, in cross-section and adapted to admit and retain a rock-shaft 20 therein, which rock-shaft is also oval in cross-section in the portion thereof within said bore, the remaining portions of said rock-shaft being 60 circular in cross-section.

The end portions of the rock-shaft 20 extend outside of the casing 15, and one end of a crank-arm 21 is rigidly secured to one of said end portions, the opposite end of said crank-arm 65 being pivotally connected to the lower end of a connecting rod 22, the upper end of which connecting rod is pivotally connected to the horizontal lever 23 at a point about mid-way of the length of the latter, which is fulcrumed 70 at one end on a standard 24 that is vertically mounted upon the cylinder 16. Adjustably positioned on the outer portion of the lever 23 is a weight 25.

The lower end of the cylinder 16 communicates with the interior of the casing 15, while the upper end of said cylinder is closed and provided with a guide, or bearing, 26, within which is mounted a piston-rod 27 provided with a link connection 28 between its upper 80 end and the said lever 23 at a point intermediate of the connecting rod 22 and the standard 24. The lower portion of the piston 27 extends within the cylinder 16, and has secured thereto a piston 29 of any suitable construction.

A standard 30 is fixed to the cylinder 16 and extends vertically therefrom to a point adjacent the lever 23, and a pin 31 is connected to the said standard and is adapted 90 to be positioned in a transverse aperture therein, and sustain the weighted lever, at times.

That portion of the casing 15 in which the valve-plug is mounted conforms upon its interior to the shape of the valve-plug, so that during rocking movement of the latter, a steam tight joint will be formed between said parts, and the slots in said valve-plug are positioned substantially in alignment with the 95 interior of the horizontal portions of the pipes 12, 14, so that the steam passing through said pipes may pass in a substantially straight line through said casing, and through the 100

slots in said valve-plug from one pipe to the other.

A very important portion of my invention is the construction and relative positioning 5 of the valve-plug 17 and the piston 29, whereby when said piston is moved abnormally inward, said valve-plug will be abnormally moved a corresponding amount and the flow of steam will thereby be cut off by it.

10 The operation is as follows: Steam emanating from the boiler 10 is conveyed through the pipe 12 and globe-valve 13 to the casing 15; and the lever 23, and parts connected thereto, being supported in normal position by the 15 pin 31 of the standard 30, the valve-plug 17 is so positioned that the slots thereof are in alignment with the pipe 12 and register with opposite slots formed in a transverse partition extending across the interior of said casing, and the steam passes through said slots into the rear portion of said casing beneath said piston, and into the pipe 14 and tank 11. Upon the entrance of steam into said tank, pressure therein and in the pipe 14 and casing 15 accumulates, and is exerted beneath the piston 29, until it raises the latter and also raises the lever 23 off of the pin 31. Prior to this, however, the weight 25 should be so positioned upon the lever 23 in accordance with the pressure desired in the tank 11. If a great pressure be desired therein, said weight should be placed adjacent the outer free end of said lever, while if a lesser pressure be desired the weight should be correspondingly moved inward and fixed in position in any common manner. As soon as the desired pressure in the tank has been reached and the lever 23 thereby raised from the pin 31, said pin 31 should be removed so 40 that said lever will be at liberty to fall below its normal position.

It is apparent that in the event of an accidental explosion, or destruction, of the tank 11, pipe 14, or any adjacent portion of the 45 casing 15, the pressure in these parts will im-

mediately be removed from beneath the piston 29, and said piston will instantaneously gravitate downward below its normal elevation, and the connections between it and the valve-plug 17 will cause the latter to move 50 in a direction the reverse of that above described, and all passage of steam from the boiler will thereby be automatically cut off from the broken part, or parts, and all damage, or injurious effects of continued escape 55 of steam from the boiler be effectually prevented.

What I claim is—

1. An automatic pressure regulator and cut-off, comprising a steam conductor, a casing communicating therewith, a valve-plug mounted for oscillation within said casing, a weighted lever, a cylinder communicating with said casing, a piston mounted within said cylinder, a standard on said cylinder, a 60 pin 31 removably mounted in an aperture in said standard beneath said lever, connections between said piston and the weighted lever, and connections between said lever and the valve-plug, whereby upon the variation of the 65 steam pressure in said casing, the horizontal plane of the piston will co-incidently vary and automatically oscillate the valve-plug, whereby the flow of steam through said valve-plug is regulated and controlled. 70

2. In a device of the class described, a valve-plug semi-cylindrical in form and having slots therein, and an axial bore oval in cross-section, in combination with a shaft oval in cross-section and inserted in said bore, and 75 lever mechanism connected with said shaft, whereby the same is actuated to oscillate the said plug.

In testimony whereof I affix my signature in presence of two witnesses.

ISAAC N. GASKILL.
